UNITED STATES PATENT OFFICE.

HAROLD A. SIMMS, OF CHICAGO, ILLINOIS.

REFRIGERATOR CAR.

Application filed September 15, 1923. Serial No. 662,863.

This invention relates to improvements in refrigerator cars.

One object of the invention is to provide an improved refrigerator car having ice chambers at opposite ends, wherein the bulk-heads forming the ice chambers are composed of hinged doors which may be readily swung open to obtain access to the chambers.

Another object of the invention is to provide a car of the character indicated having ice chambers at the ends thereof, provided with bulkheads which are adapted to be swung aside, whereby the space provided for the ice chambers may be made available for carrying freight when the car is not used as a refrigerator.

Another object of my invention is to provide a refrigerator car having the ice compartment so constructed that repair of any part may be made at any time without destroying the bulk-head as is now commonly necessary where the bulk-head is fixed or permanent with respect to the walls of the car.

A still further object of my invention is to provide a refrigerator car having an ice chamber with bulk-heads so constructed that they may be readily opened and access immediately obtained to the ice compartment to remove such ice as may be therein at the end of a trip, and have the car made immediately available for transporting dry freight.

Other objects and advantages of the invention will more clearly appear from the description and claims hereinafter following.

In the accompanying drawings, forming a part of this specification, Figure 1 is a vertical, transverse, sectional view through a refrigerator car, corresponding substantially to the line 1-1 of Figure 3, and showing my improvements embodied therein. Figure 2 is a horizontal, sectional view, corresponding substantially to the line 2-2 of Figure 1. Figure 3 is a vertical, longitudinal sectional view, corresponding substantially to the line 3-3 of Figure 1. And Figure 4 is a horizontal, sectional view through a bulk-head, corresponding substantially to the line 4-4 of Figure 1.

In said drawings, 10 indicates the roof, 11 the floor, 12-12 the insulated side walls and 13 one of the insulated end walls of a refrigerator car. The car also has an insulated ceiling 14 and the side and end walls are provided with the usual inner sheathing 15. At each end of the car and spaced from the adjacent end wall thereof is a transversely ex-

tending bulkhead A, the bulkhead at one end of the car only being shown in the drawing. The bulkheads A divide the car into a large central and two relatively small end compartments, thereby providing ice chambers or compartments B at the opposite ends of the car. Immediately above each of the respective ice chambers B and communicating therewith are provided a pair of hatches 16 through which the cars are adapted to be iced, the hatches 16 of each pair being disposed on opposite sides of the longitudinal center of the car. The hatches 16 are of usual and well-known construction, each being provided with 70 an insulated door 17 tightly sealing the hatch opening and a hatch cover 18.

The bulkheads A, at the opposite ends of the car are of like construction, each comprising a pair of swinging doors 19 and 20, 75 the doors 19 and 20 being hinged respectively adjacent the side walls of the car, to the outer sides of vertically disposed door posts 21 at opposite sides of the car. The doors 19 and 20 are of substantially the same construction, 80 each comprising vertically disposed outer and inner heavy side timbers 22 and 23; horizontally disposed heavy cross timbers 24, 25 and 26; spaced apart front and back walls 27 and 28; a vertically extending center brace 29; 85 and a diagonally extending cross brace 30. The cross timber 24 of each door forms the upper edge thereof and the cross timbers 25 and 26 are spaced an appreciable distance from the upper and lower ends of the door 90 respectively, thereby providing upper and lower air circulating openings in each door. The walls 27 and 28 of each door span the space between the side timbers 22 and 23 and extend from the timber 25 to the timber 26. 95 The center and cross braces 29 and 30 are disposed in the space between the walls and extend between the timbers 25 and 26, the brace 29 being adjacent the wall 28 and the brace 30 being adjacent the wall 27, the latter extending from the outer lower corner to the upper inner corner of the walled portion of the door. The doors are preferably properly insulated by interposing four-ply insulation between the walls 27 and 28, as indicated at 31.

The corners of the opening at the upper end portion of each door are braced by pairs of metal strip members 32 extending vertically and fixed to the timbers 22 and 23 110 respectively, and having upper and lower inwardly projecting right-angular extensions

fixed to the timbers 24 and 25, the straps being in this instance shown as held by bolts passing through the respective timbers, although any other suitable fastening devices 5 may be used.

The opening at the lower end of each door has the walls at the upper corners thereof braced by a pair of angle straps 33 secured to the cross timber 26 and the timbers 22 and 23, respectively, by bolts or any other suitable fastening devices. The bottom wall of the opening at the lower end of each door is formed by a section of metal strip 34 which also forms the lower edge of the door. The 10 opposite ends of the strip 34 are bent upwardly at right angles to the major portion thereof and are bolted or otherwise secured to the inner sides of the timbers 22 and 23. The major portion of the strip 34, which extends between the timbers 22 and 23, is inclined transversely to the horizontal, as clearly shown in Figure 3, whereby the rear edge thereof is disposed above the front edge and is offset with reference to the lower edge 15 of the door.

The openings at the upper and lower ends of each door are spanned, respectively, by protective wire nettings 35 and 36 set into the front surfaces of the respective timbers 20 along the edges of the openings, the netting 35 being clamped in place by four metal strips 134, secured respectively to the timbers 22, 23, 24 and 25, and the netting 36 being clamped in place by three similar metal strips 38 secured respectively to the timbers 22, 23, and 26 and a fourth somewhat wider strip 39 riveted or otherwise secured to spaced angle members 40 riveted to the strip 34.

The back of each of the doors 19 and 20 is also provided with a protecting netting or screening 41 completely covering the wall 28 of each door and the opening at the upper end thereof, the netting 41 being spaced with reference to the wall 28 of the door by vertically extending strips 42 secured to the back of the door, the space between the netting and the door providing an air circulating passage. The upper end portions of the strips are beveled or inclined upwardly toward the 45 door terminating adjacent the upper opening in the same, and the corresponding portion of the screen 42 is similarly inclined, the upper end portion of the latter being offset toward the door and seated in a rabbet 50 surrounding the opening. To protect the vertical edge portions of the netting 41 adjacent the inner edge of the door, each door is provided with a vertically extending section of angle bar 92 having one arm thereof bolted 55 to the corresponding edge timber 23 and the other arm projecting at right angles to the door beyond the adjacent edge of the netting.

Each of the doors 19 and 20 is provided with upper and lower hinge straps 43 and 44, 60 each pivotally connected by means of a hinge

pin to a co-acting hinge strap 45 secured to one of the door posts 21, the straps 45 being disposed between each respective side wall of the car and the adjacent post 21 at each end of the car, as clearly shown in Figures 1 and 70 2. Each of the straps 43 extends entirely across the front of the corresponding door, is bolted or otherwise secured to the top cross timber 24 and has its end terminating adjacent the meeting edges of the doors turned outwardly at right angles to provide a locking bolt receiving lug 46. The lug 46 on the strap of the door 20 is in alignment with the edge of the door, while the lug 46 of the strap of the door 19 is spaced inwardly from the 75 edge of the latter. The door 19 is also preferably provided with an eye bolt 47 adjacent the upper end thereof, extending through the timber 23 and having the eye thereof extending between the lugs 46 when the doors are 80 closed. The lugs 46 are perforated in alignment with the eye of the bolt to receive a locking bolt 48 adapted to be inserted through the same and the eye of the bolt, said locking bolt having a gravity member 49 pivoted to the end thereof adapted to prevent 85 accidental removal of the locking bolt.

Each of the straps 44 also extends entirely across the front of the corresponding door, is bolted or otherwise secured to the cross-timber 95 26, and has the end thereof terminating adjacent the meeting edges of the doors provided with locking bolt receiving means, comprising a pair of vertically spaced bolt receiving eye members 50 on the strap 44 of the door 20 and a corresponding bolt receiving eye member 51 on the strap 44 of the door 19. The door 20 is also preferably provided with an eye-bolt 52 adjacent the edge thereof, extending through the timber 23 and having the eye 100 thereof disposed between the eye member 51 and the lowermost member 50, with the opening thereof aligned with the opening of said hinge members to receive a locking bolt 53, the adjacent edges of the doors being cut away to 105 accommodate the locking bolt 53. As will be evident from the preceding description, the doors 19 and 20 at each end of the car are so hinged as to lie flat against the side walls of the car when swung to fully opened position, 110 as clearly shown in dotted lines in Figure 2, thereby occupying the minimum amount of space when the car is converted for carrying ordinary freight.

As clearly shown in Figure 4, the meeting edges of the doors 19 and 20 are beveled so as to match and wedge tightly together when closed. Anti-friction rollers 150 are also, preferably, provided at the lower ends of the doors 19 and 20, the same being set into 115 the lower ends of the timbers 23. The rollers 150 are adapted to roll on the floor 11 when the doors are swung on their hinges, thereby preventing undue strain being placed on the latter and giving the doors an easy move- 120 130

ment. A pair of angle bars 54 and 55, extending transversely of the car and coacting respectively with the timbers 24 and 26 of each set of doors 19 and 20, function as door stops. Inward movement of the door is also arrested by a member 56 fixed to the floor 11 and extending transversely of the car, with which the lower ends of the door timbers 22 and 23 are adapted to abut. The angle 54 has one arm thereof horizontally disposed and suitably secured to the ceiling 14 of the car and has the other arm thereof disposed vertically to act as an abutment for the doors. A latch 151, having one end thereof pivoted within the housing 152 set into the floor, is adapted to be swung into position in front of the doors 19 and 20 as shown in Fig. 1 to retain the doors in closed position, the housing being of a size to permit the latch to drop 20 into the same so as to entirely clear the lower edges of the doors.

The angle bar 55 is suitably secured to short, vertical posts 57 disposed at intervals across the car, there being preferably four 25 such posts at each end of the car, one adjacent each side wall and one at each side of the center line of the car, all of said posts being equally spaced apart. The posts 57 are in the form of I-beams cut out at their lower 30 ends to accommodate the member 56 and having the downwardly extended portions 58 thereof, extending into and supported by the drip pan 76. The upper ends of the posts 57 are provided with angles 59 fixed thereto, and 35 to the lower horizontal arm of the bar 55 by rivets or any other suitable means. The angle bar 55 normally has the other arm vertically disposed and adapted to act as an abutment for the doors. The posts 57 and angle 40 bars 55 at each end of the car are further braced by four flat bars 60 extending longitudinally of the car. Each angle bar 55 together with the posts 57 fixed thereto is hinged to the bars 60 of the corresponding ice 45 chamber grating 66 by means of a plurality of hinge members 61, each having the straps thereof riveted to one of the bars 60 and the corresponding I-beam 57, respectively. The opposite end of each bar 60 is normally supported by a Z-bar 62 extending transversely 50 of the car and fixed to the horizontally extending cross timber 63 of the car by bolts 64 or any other suitable means. The Z-bar is also supported by a cross timber 65 on 55 which it rests.

Each of the ice chambers A is provided with an ice supporting grating 66 extending from side to side of the car, the grating being composed of a plurality of sets of wooden 60 bars 67 having rounded upper surfaces. In the present instance, three sets of bars are shown, the bars of each set preferably extending transversely of the car, and supported at their opposite ends upon beams 68 extending longitudinally of the car, and

each bolted to one of the bars 60. Each set of grating bars are held together by tie bolts 69 extending therethrough, and adjacent bars of each set are spaced apart by separating ferrules 70 on the bolts 69. Each 70 section of grating 66 is securely held to the beams 68 by bolts 71 anchored to brackets 72 secured to the opposite side faces of the beams 68, and co-acting with clamping plates 73, each adapted to engage over the end portions of two adjacent bars 67. Four sets of clamping bolts 71 and plates 73 are preferably provided for each section of grating, one set at each corner of the same.

Within the ice chambers B, the inner 80 sheathing 15 of the side and end walls of the car is preferably provided with netting 74 extending from the ceiling to a point below the upper surface of the grating, preferably extending in close proximity to the upper 85 surfaces of the beams 68. The netting 74 is spaced from the sheathing by vertically disposed spacing and nailing strips 75 to which the netting 74 is secured, said strips 75 being suitably fixed to the sheathing 15. A 90 space is thus provided between the sheathing and the netting to provide for circulation.

The gratings 66 are supported for swinging movement by hinge members 174 having the straps thereof secured respectively to 95 each grating 66 and blocks 175 secured to the sheathing 15 at each end of the car. The gratings may thus be swung vertically out of the way to the dotted line position in Figure 3, when desired, to make the space normally occupied by the ice chambers available for transporting freight. As the posts 57 are also hinged to the gratings, it will be evident that the same will be folded as indicated in dotted lines in Figure 3. To 100 retain the gratings 66 in the dotted line position, a plurality of hooks 176 are preferably provided, each of the same being pivotally secured to one of the strips 75 by means of a staple 177, each of said hooks 110 being adapted to co-act with a corresponding eye 178 secured to the grating.

Below the grating 66 is provided a sheet metal drip pan 76, preferably formed of galvanized iron. The drip pan 76 is of rectangular shape and has the rear wall 77 thereof extending between the Z-bar and the beam 65 thereby preventing moisture from coming into direct contact with the timber 65. The front wall 78 of the drip pan is 120 bent angularly so as to conform to the member 56 and protect the upper and inner side faces thereof from moisture.

From the preceding description, considered in connection with the drawings, it will be 125 noted that I provide for a circulation of the air such that the cold air passes downwardly through the ice grating at the bottom of the ice chamber, thence outwardly into the main compartment of the car through the 130

bottom ventilating openings of the bulkhead doors, the warmer air entering the ice chamber through the top ventilating openings of the bulkhead doors and passing down-
5 wardly through the ice chamber. It will also be noted that the downward circulation of the air through the ice chamber is permitted adjacent the side walls of the car, the end wall of the car and on the inner
10 sides of the bulkhead doors, so that proper and efficient circulation of the air through and around the ice is always assured.

When it is desired to obtain access to the ice chambers for any purpose, the bolts 48
15 and 53 are withdrawn, whereupon the doors may be swung to the dotted line positions shown in Figure 2. It will be evident that where the car is not to be used for commodities requiring icing in transit, the entire
20 length of the same may be made available for carrying other commodities by merely throwing the doors to the position shown in Figure 2, raising the gratings 66 to the position shown in Figure 3, securing the same
25 by the hooks 176 and folding the posts 57 against the bars 60.

I have herein shown and described what I now consider the preferred manner of carrying out my invention, but the same is
30 merely illustrative, and I contemplate all changes and modifications that come within the scope of the claims appended hereto.

I claim:

1. In a refrigerator car, the combination
35 with a foldable bulkhead separating said car into compartments; of means for supporting said bulkhead and means for bracing said bulkhead against torsional movement, said means including transversely arranged
40 spaced members extending across said bulkhead and bearing against said supporting means when said bulkhead is in operative position.

2. In a car, the combination with a bulkhead comprising a pair of doors extending transversely of the car to divide the same into compartments; and means for hinging said doors adjacent the side walls of the car for swinging movement about vertical axes,
50 whereby, said doors may be swung to a position closely adjacent said side walls; and means for bracing said doors against torsional movement, said means including transversely disposed, spaced members adapted to bear against each other and transmitting stress to said supporting means.

3. In a car, the combination with a bulkhead extending transversely of said car and normally separating the car into compartments, one of which serves as an ice chamber, said bulkhead comprising a pair of doors hinged adjacent the side walls of the car and adapted to be swung to positions adjacent said side walls; of means for bracing said
65 doors against torsional movement, said

means including transversely disposed, spaced members adapted to bear against each other and to transmit stress lengthwise thereof; and means for locking said doors in closed positions when disposed transversely of said car, said locking means being associated with said bracing members.

4. In a car, the combination with a pair of transversely extending bulkheads at opposite ends of the car dividing the same into a central freight compartment and a pair of ice chambers at opposite ends of the car, said bulkheads being composed of sections swingable to positions approximately parallel to the sides of the car; of means for bracing said door against torsional movement, said means including bracing members adapted to bear against each other, and to transmit stress lengthwise thereof; and means for locking said doors in closed position, said doors being provided with beveled meeting faces.

5. In a refrigerator car, a pair of doors hinged adjacent the side walls of the car and adapted to be disposed in position at right angles to said walls to provide a bulkhead and also adapted to be swung to positions adjacent said side walls; and means for bracing said doors against torsional movement, said means including transversely disposed, spaced members adapted to bear against each other and to transmit stress lengthwise thereof; said doors being insulated and provided with ventilating openings at the top and bottom.

6. In a refrigerator car, the combination with a pair of doors forming a bulkhead, of means for hinging said doors, said means including hinge straps on each door extending entirely across the same; and means on said straps for receiving locking bolts to lock said doors in closed position.

7. In a refrigerator car, the combination with a bulkhead separating the car into compartments, one of which is an ice chamber; of means within said ice chamber for supporting ice, including a grating; supports for said grating including a Z-bar having a downwardly extending leg; and a drip pan beneath said grating, said pan having a portion of one of the walls thereof overlapped by said leg.

8. In a refrigerator car, the combination with a transversely extending swingably mounted bulkhead on the interior of the car, thereby providing an ice chamber between said bulkhead and the end wall of the car, said bulkhead having ventilated upper and lower openings permitting circulation of air through the bottom openings into the main compartment of the car and from the latter through the upper openings into the ice chamber; an ice supporting platform within the ice chamber; and means, part of which are carried by said bulkhead, providing vertically disposed air circulating passages on all

four sides of the ice chamber, said passages communicating with said ice chamber by means of a plurality of openings in the walls which define said chamber.

5 9. In a refrigerator car, the combination with a bulkhead comprising a pair of doors hinged on vertical axes and providing an ice chamber, said bulkhead having ventilating openings; and means part of which are carried by said bulkhead forming retaining walls of said ice chamber, said walls being arranged to provide air circulating passages on its various sides, the walls having a plurality of openings communicating with said

15 air passages.

10. In a convertible car, the combination with a bulkhead comprising a pair of doors hinged adjacent the side walls of the car, said doors, when closed, dividing the car into compartments, one of which is an ice chamber; of ice supporting means swingably connected to the end wall of the car; and means for supporting the forward edge of said supporting means, including a plurality of spaced posts secured to a connecting bar upon which said supporting means are adapted to rest, said bar and said posts being hingedly connected to said supporting means.

11. In a convertible car, the combination with a bulkhead comprising a pair of doors hinged adjacent the side walls of the car, said doors, when closed, dividing the car into compartments, one of which is an ice chamber; of ice supporting means pivotally connected to the end wall of the car and adapted to be swung into position against said end wall; and means for supporting the forward edge of said supporting means, including a transversely arranged angle bar having a plurality of spaced posts secured to one angular flange thereof, the other angular flange extending vertically outwardly of the free

forward edge of said supporting means to act as a door stop when said supporting means are in operative position, said angle bar and 45 said posts being hingedly connected adjacent the forward portion of said supporting means.

12. In a refrigerator car, the combination with a bulkhead comprising a pair of doors 50 forming a bulkhead; of means for hinging said doors to swing about vertical axes, said means including hinge straps on each door extending the entire width across the same, said bulkhead providing an ice chamber and 55 having ventilating openings therein; and means, part of which are carried by said bulkhead, forming retaining walls of said ice chamber, said walls being arranged to provide air circulating passages on its various 60 sides, the walls having a plurality of openings communicating with said air passages.

13. In a refrigerator car, the combination with a pair of doors forming a bulkhead for said car; of means for hinging said doors to 65 the car walls to swing about vertical axes, said means including spaced hinged straps on each door extending entirely across the same, the hinge straps of each door being disposed longitudinally in alignment with the 70 hinge straps of the other door; and means for rigidly locking the free ends of said straps together when the doors are in closed position, said means serving to maintain the doors closed, said hinge straps, when locked together, providing rigidifying braces extending entirely across the bulkhead so as to resist distortion thereof in operation of the car.

In witness that I claim the foregoing I 80 have hereunto subscribed my name this 21st day of August 1923.

HAROLD A. SIMMS.
